UNITED STATES PATENT OFFICE.

JACKSON DAVIS SCHOOLER, OF SEDALIA, MISSOURI.

DOOR-HANGER.

SPECIFICATION forming part of Letters Patent No. 621,155, dated March 14, 1899.

Application filed November 26, 1898. Serial No. 697,531. (No model.)

To all whom it may concern:

Be it known that I, JACKSON DAVIS SCHOOLER, of Sedalia, in the county of Pettis and State of Missouri, have invented a new and 5 Improved Door-Hanger, of which the following is a full, clear, and exact description.

The invention relates to sliding doors, principally such as used on freight-cars, barns, dwellings, &c.; and the object is to provide 10 a new and improved door-hanger which is simple and durable in construction, not liable to get out of order, and arranged to permit a convenient opening and closing of the door without danger of binding in the tracks.

15 The invention consists of novel features and parts and combinations of the same, as will be fully described hereinafter and then pointed out in the claims.

Reference is to be had to the accompanying 20 drawings, forming a part of this specification, in which similar characters of reference indicate corresponding parts in all the views.

Figure 1 is a partial side elevation of the improvement, with parts in section. Fig. 2 25 is an enlarged transverse section of the same on the line 2 2 in Fig. 1, and Fig. 3 is a face view of the washer for the eyebolt.

The door A is provided on its upper end with hangers B, journaled at their extreme upper ends on balls C, mounted to travel in a longitudinally-extending tube D, formed with a split D' at its bottom for the passage of the hangers B. The ends of the tube D are closed by caps E, and said tube is supported on eyebolts F, secured on a fixed part of the doorframe G, as is plainly indicated in Fig. 2, 30 each bolt having its eye F' split at the bottom, said split being in alignment with the split D' to insure a free travel of the hangers B past the eyebolts F.

Each eye F' is opened at F² at that part attached to the shank F³, so that the opened-up portion extends in a horizontal plane through the axis of the shank, as will be readily understood by reference to Fig. 2. The 45 opened-up portions of the eyes are inclined

at their outer faces to engage the beveled faces of a washer H, through which the bolt passes and is held in a fixed part of the doorframe.

Now it is evident that when the nut F⁴ on the eyebolt F is screwed up then the eye is drawn into the washer, and said washer H closes the two portions of the eye at the split F², which causes the eye to firmly clamp the tube D, so as to hold the latter securely in place and prevent the tube from turning or sliding in the eyes of the bolts F. Thus it will be seen that by the simple means described the tube D is always held in proper 55 position and the balls C are free to travel in said tube D without danger of binding therein or of the hangers B being bound in the split ends of the tube.

Having thus fully described my invention, 60 I claim as new and desire to secure by Letters Patent—

1. A door-hanger comprising a split tube, balls mounted to travel in said tube, hangers supporting the door and journaled on said 70 balls and extending through the split in the tube, eyebolts having open eyes and split shanks for engaging and supporting the tube, the openings in the eyebolts being in alignment with the split in the tube, and washers 75 for said eyebolts adapted to close the splits in the shanks of said eyebolts, and clamp the eyes thereof upon the tube and hold the latter clamped against movement, substantially 80 as shown and described.

2. A door-hanger, provided with an eyebolt having a shank, and an open eye, the portion of the eye connected with the shank being split in a plane passing through the axis of the shank and the opening in the eye being 85 transverse to the direction of the slit, substantially as shown and described.

JACKSON DAVIS SCHOOLER.
